UNITED STATES PATENT OFFICE.

PERCY E. HUNTER, OF PITTSBURGH, PENNSYLVANIA, ASSIGNOR OF ONE-HALF TO
BERNARD WEST, OF WEIRTON, WEST VIRGINIA.

TINNING POT.

Application filed June 24, 1927. Serial No. 201,115.

My invention refers to improvements in the class of tinning posts for application of molten tin to the surfaces of black iron sheets. In such operation the sheet is usually introduced downwardly through a bath of molten tin and then upwardly, with a final passage through a superimposed body of oil, as palm oil.

In my present invention I provide oppositely arranged water circulating cooling walls at each side of the oil containing chamber with means for providing a copious water circulation therethrough, and for cleaning out deposits of sediment from time to time.

Also an improved construction of the initial tinning compartment providing for continuous renewal supply of pig tin, together with other features of construction and improvement, as hereinafter described.

In the drawings, showing one preferred embodiment of the invention,—

Fig. 1 is a plan view of the pot;

Fig. 2 is a cross section on the line II, II, of Fig. 1;

Fig. 3 is a longitudinal vertical section on the line III, III, of Fig. 1;

Fig. 4 is a similar section on the line IV, IV, of Fig. 1;

Fig. 5 is a detail section on the line V, V, of Fig. 2;

Fig. 6 is a similar horizontal section on the line VI, VI, of Fig. 2.

The main body of the pot consists of a continuous U-shaped blank of plate metal bent to provide a front wall 2, a bottom wall 3, a rearwardly inclined back wall 4, and an upper rear vertical wall 5.

The latter wall extends materially higher than front wall 2, providing for one side of the superimposed oil chamber B.

The ends of the pot are formed by closing end walls 6 of a suitable metal plate form, adapted to make a welded or other suitable connection with the ends of the main wall section 2—3—4—5.

For such purpose the end walls are generally L-shaped, providing for the two main sections of the pot, and are welded or otherwise secured thereto throughout the section 2—3—4—5 as shown in Fig. 5. In order to ensure strength and a good retaining connection throughout, the end walls 6 fit within the continuous outer flanges 7 of the sec-

tion 2—3—4—5 so that the flange is continuously welded around the outer edge portions of the end plate at all points.

The flange 7 being firmly welded to the edges and sides of the end plate, as at 8, not only provides a continuous homogeneous joint, but likewise provides a continuous strong retaining reinforcement throughout the entire length of the joint, at each end.

A middle longitudinal partition 9 extends from the bottom 3 upwardly to the same level with the top of rear wall 5, dividing the main tinning compartment into two chambers A and a respectively.

The lower portion of wall 9 is provided with a longitudinal opening 10 for passage of the plates from chamber A to chamber a and is welded to the bottom 3, as at 11.

Upwardly beyond the top of chamber A partition 9 is welded to the end walls as at 12, as in Fig. 6.

In this manner the parts are firmly connected and braced, and the end wall is retained against pressure of the oil in chamber B.

The lower front portions of the end plates 6 are provided along their upper edges with reinforcing flanges 13 joined with a similar front flange 14 of the wall 2, and welded thereto as at 15, the corners being preferably rounded as shown.

The lower front portions of the end plates 6 are provided, at one or both ends, with pockets 16 formed by outwardly extending rectangular flat or inclined bottomed boxes 17, secured against the outer upper portions of the end plates, or in any other suitable manner. These pockets are each provided with inner cross bars 18 for retention of the pig tin bar or ingot 19. Such bars are supplied from time to time, extending well below the level of the tinning bath in chamber A, and replenish the supply by melting down under the heat of the bath.

For the purpose of cooling the oil in chamber B, I provide water circulating boxes or chambers c, d, respectively.

These are formed by welding or otherwise securing outer enclosing walls 20 and 21 to the rear of wall 5 and to the front of partition 9 respectively, as in Fig. 2. The boxes c and d extend along the main middle portion of said walls, for the major portion of the oil com-

partment, and are preferably welded at top, bottom and ends, as at 22.

The rear cooling chamber thus formed preferably extends vertically, while the front chamber preferably inclines forwardly as shown, in conformity with the inclined section '23 of partition 9. Such arrangement gives additional clearance for the usual rolls.

The cooling boxes as thus made form enclosed compartments, to which water is supplied by pipes 24 having plural branch supply connections 25 extending downwardly through the tops of the boxes, to near their bottoms.

15 Waste pipes 26 lead from one or both ends, preferably at the upper portions of the boxes, for carrying off the heated water, after circulation therethrough.

For the purpose of cleaning out sediment, 20 etc., from the boxes from time to time, openings 27 and 28 are provided at opposite ends of the cooling boxes, near their bottoms, closed by plugs 30, whereby they may be flushed out from time to time, by a hose.

25 The construction and operation of the tinning pot as above described will be readily understood and appreciated by those skilled in the art. The plates are introduced and withdrawn in the usual manner in connection 30 with mechanism and implements of suitable kind.

The supply of pig tin, lead, or other suitable metal is rendered easy and automatic by means of the feeding pockets, while the oil 35 may be maintained at a suitably low temperature by control of the water circulation through the water boxes at each side of the oil compartment.

The construction may be changed or varied 40 in different features or details within the province or design of the builder or skilled mechanic, but all such changes are to be understood as within the scope of the following claims.

45 What I claim is:—

1. A tinning pot consisting of a continuous body portion forming front, bottom and rear walls, a longitudinal partition therein, and end plates having coating metal supply pockets opening to the interior.

2. A tinning pot consisting of a continuous body portion forming front, bottom and rear walls, a longitudinal partition therein, and end plates having embracing flanges secured thereto and provided with coating metal supply pockets opening inwardly to the interior. 55

3. A tinning pot consisting of a continuous body portion forming front, bottom and rear walls, a longitudinal partition therein, and end plates having embracing flanges secured thereto and provided with coating metal supply pockets opening inwardly to the interior, 60 said pockets having a supporting bottom and retaining cross bars.

4. In combination with the wall of a tinning pot, a water containing cooling chamber consisting of a closed box-like wall secured along on the outer side of the wall and provided with water circulating pipes. 65

5. In combination with the wall of a tinning pot, a water containing cooling chamber consisting of a closed box-like chamber formed of a casing located along on the outer side of the wall, and provided with water circulating pipes and supplemental water circulating cleaning openings. 75

6. In combination with the upper oil containing walls of a tinning pot, oppositely located longitudinally arranged water circulating chambers consisting of closed wall boxes 80 mounted upon the main walls having water circulating pipes extending downwardly through the tops of the boxes, and exhaust pipes connected with the upper end portions of the boxes. 85

7. In combination with the upper oil containing walls of a tinning pot, oppositely located longitudinally arranged water circulating chambers consisting of closed wall boxes mounted upon the main walls having water circulating pipes extending downwardly through the tops of the boxes, exhaust pipes connected with the upper end portions of the boxes, the lower end portions of the boxes having water circulating cleaning openings and closing plugs therefor. 90

In testimony whereof I hereunto affix my signature.

PERCY E. HUNTER.
